Hugo Aderer;

By William L. Szymous
his Attorney

UNITED STATES PATENT OFFICE.

HUGO ADERER, OF EAST ORANGE, NEW JERSEY.

DENTAL CLASP.

Application filed December 6, 1923. Serial No. 679,010.

To all whom it may concern:

Be it known that I, HUGO ADERER, a citizen of the United States of America, residing at 82 South Parkway, East Orange, in the county of Essex and State of New Jersey, have invented certain new and useful Improvements in Dental Clasps, of which the following is a specification.

My invention relates to the construction 10 of a ready made dental clasp.

Some of the objects of my invention are: first, the construction of a ready made clasp of two parts, the parts being joined together so that the clasp when delivered to the dentist is ready for use; second, the construction of a clasp having a shoulder on the band and a shoulder on the tail-piece, these shoulders equalizing the stress between the two parts; third, the construction of a clasp having a shoulder on the band co-operating 20 with a shoulder on the tail-piece in such manner that the upward and downward movement of these parts with respect to each other may be adjusted and also that the play 25 between the tail-piece and the band may be adjusted; and, fourth, to make the connecting parts of the band and tail-piece of the clasp integral and thus to avoid soldering any of the parts.

With these and other objects in view, an embodiment of my invention is shown in the accompanying drawings, in which:

Figure 1 is a top plan view;

Figure 2 is a section on line 2—2 of Figure 1;

Figure 3 is a section on line 3—3 of Figure 1;

Figure 4 is a plan view of the band flattened out and before the shoulder is formed 40 thereon;

Figure 5 is a plan view of the tail-piece before the shoulder has been formed thereon;

Figure 6 is a side elevation showing the clasp attached to the natural teeth, said 45 clasp being connected with an artificial denture;

Figure 7 is a side elevation showing a modified form of tail-piece and an unslit band; and

Figure 8 is a side elevation showing another modified form of tail-piece and an unslit band.

My clasp may be made of any suitable material, such as gold clasp metal, and comprises a band 1 adapted to partially encircle 55 a tooth. This band, in the form shown in

Figures 1, 2, 3, 4, and 6, has slits 2 forming fingers 3, while the band shown in Figures 7 and 8 is not slit. The band may have a cusp 4 as an integral part thereof. The band 60 is attached to the tail-piece 5 by means of a hook 6 made by extending outward from the plane of the band and then bending upward the extension of the band shown in Figure 4 substantially parallel with the 65 plane of the band. The upper end of the hook may be split, as indicated at 7, to fasten the band and tail-piece together after the tail-piece having one end bent at substantially a right angle to the plane of the 70 tail-piece to form a shoulder 8 has been placed over the hook, the hook passing through the opening 9 in the tail-piece. The vertical movement may be regulated by the depth of the split as illustrated in 75 Figure 3. This hook may be placed at different angles with respect to the plane of the band, as illustrated in Figure 2. The strength of the tail-piece may be increased by a re-inforcement as indicated 80 at 5^a. In Figure 7, the tail-piece is shown without the re-inforcement 5^a and the band is not slit. In Figure 8, the tail-piece forms a casing or covering for the hook. This casing prevents the rubber in which the tail-piece 85 may be embedded from flowing into the attachment and interfering with the movement between the tail-piece and the band.

In Figure 6 the use of my clasp is illustrated. Natural teeth 10 are shown having a clasp surrounding one of them, and with the tail-piece of the clasp inserted in an artificial denture 11 having the usual false teeth 12.

It will be evident from the description given that this connection allows the band and the tail-piece to be raised or lowered with respect to each other and that the connection also allows for angular, lateral, and rocking movement between the artificial denture and the band of the clasp.

Having described my invention what I claim and desire to protect by Letters Patent is:

1. A dental clasp comprising a band and a tail-piece, said band having integral therewith tail-piece engaging means, said tail-piece having an end thereof at an angle to the plane of said tail-piece, said tail-piece having an opening therein through which said tail-piece engaging means is adapted to

- be inserted and means to prevent the separation of the tail-piece and the band.
2. A dental clasp comprising a band and a tail-piece, said band having tail-piece engaging means thereon, said means being adjustable as to the angle between said means and said band, said tail-piece having an opening therein through which said tail-piece engaging means is adapted to be inserted and means to prevent the separation of the tail-piece and the band.
3. A dental clasp comprising a band and a tail-piece, said band having integral there-with tail-piece engaging means, said means being adjustable as to the angle between said means and said band, said tail-piece having one end thereof at an angle to the plane of said tail-piece, said tail-piece having an opening therein through which said tail-piece engaging means is adapted to be inserted and means to prevent the separation of the tail-piece and the band.
4. A dental clasp comprising a band and a tail-piece, said band having integral there-with tail-piece engaging means, said means being adjustable as to the angle between said means and said band, said tail-piece having one end thereof at an angle to the plane of said tail-piece, said tail-piece having an opening therein through which said tail-piece engaging means is adapted to be inserted and means to prevent the separation of the tail-piece and the band, said last named means being adjustable to vary the upward and downward movement between the band and the tail-piece.

5. A dental clasp comprising a band and a tail-piece, said band having tail-piece engaging means thereon, said means extending outward from said band and then upward substantially parallel with the plane of the band, said tail-piece having an opening therein through which said engaging means is adapted to be inserted to form a connection between said band and said tail-piece whereby vertical, lateral, angular, and rocking movement between said band and said tail-piece are obtained and means to prevent the separation of the tail-piece and the band.

6. A dental clasp comprising a band and a tail-piece, said band having integral there-with tail-piece engaging means, said tail-piece having an end thereof at substantially a right angle to the plane of said tail-piece, said tail-piece having an opening therein through which said tail-piece engaging means is adapted to be inserted and means to prevent the separation of the tail-piece and the band.

7. A dental clasp comprising a band and a tail-piece, said band having integral there-with tail-piece engaging means, said tail-piece having an end thereof at substantially a right angle to the plane of said tail-piece, said tail-piece having an opening therein through which said tail-piece engaging means is adapted to be inserted, and a casting on one end of said tail-piece to be placed over the tail-piece engaging means.

In testimony whereof I affix my signature.

HUGO ADERER.
